CLAIM

The ornamental design for a handheld microporation device, in accordance as shown and described.

DESCRIPTION

FIG. 1 illustrates a perspective view of a handheld microporation device according to a specific example embodiment of the disclosure;

FIG. 2 illustrates a left side elevation view thereof;

FIG. 3 illustrates a right side elevation view thereof;

FIG. 4 illustrates a top plan view thereof;

FIG. 5 illustrates a bottom plan view thereof;

FIG. 6 illustrates an enlarged front elevation view thereof, and,

FIG. 7 illustrates an enlarged rear elevation view thereof.

As indicated in the description above, FIGS. 1-7 present a specific embodiment of a handheld microporation porator. The features shown in broken lines depict environmental subject matter only and form no part of the claimed design.
